UNITED STATES PATENT OFFICE.

ALFRED B. SMITH, OF TOPEKA, KANSAS.

ANIMAL-HOPPLE.

1,278,239.

Specification of Letters Patent. Patented Sept. 10, 1918.

Application filed April 9, 1917. Serial No. 160,639.

To all whom it may concern:

Be it known that I, ALFRED B. SMITH, a citizen of the United States, residing at Topeka, in the county of Shawnee and State of 5 Kansas, have invented certain new and useful Improvements in Animal-Hopples, of which the following is a specification.

This invention is an animal hopple intended for use on cows to prevent them from 10 kicking and to hold them still during milking, and is an improvement on the device of similar general nature set forth in Patent No. 858,633, granted to me July 2, 1907.

The object of the present invention is to 15 improve the means for fastening the loops to the shackles, by the use of a flexible fastening comprising relatively large eyelets engaging in holes through the shackle, and the parts being so arranged that when the application is on the animal's legs the eyelets are 20 projected inwardly and serve as a very effective means for locking the shackle on the leg, and when the shackle is to be applied to or removed from the leg, the eyelet is turned 25 so as to permit the shackle to be slipped easily on or off. A further object is to provide an extension on the slotted chain locking member to facilitate the releasing of the chain.

30 In the drawings accompanying and forming part of this specification and in the description of the drawings, I have shown my invention in its preferred form and what I deem to be the best mode of applying the 35 principles thereof; but it is to be understood that, within the scope of the appended claims, I contemplate changes in form, proportions and materials, the transposition of parts and the substitution of equivalent 40 members, without departing from the spirit of my invention.

Figure 1 is a plan view of my improved device, the parts being approximately in the 45 position occupied when applied to the animal's legs. Fig. 2 is a view of the shackle to which the chain is permanently attached, the chain being partly broken away. Fig. 3 is a view of the shackle to which the chain is adjustably attachable.

50 Similar reference characters indicate similar parts throughout the several views.

The two shackle members 4, 5 are formed of metal plates or bands to fit rather snugly around the back and sides of the ham 55 strings of a cow, and each has the two holes 7, 7 adjacent to the end of one of its legs,

the outside leg when the shackle is on the cow, and the ends being bent slightly outwardly, as shown at 6, 6, to facilitate slipping the shackles onto the cow's legs. To 60 each shackle is secured a loop 8, 11, by means of relatively large eyelets 9, 9 which engage in the respective holes. To one of the loops is secured one end of a chain 10 which is passed through the other loop and provided 65 at its end with a ring 14. The outer end of the loop 11 is formed as a slot communicating with the opening through the loop and is adapted to receive a link of the chain 70 edgewise while the next link, being crosswise of the slot, holds the chain from slipping through. The extreme end of this loop has an extension 13, which is made by merely twisting the end of the slot portion. Preferably the loops are made of wire or metal 75 rods formed into the shapes shown. After the parts are assembled the chain cannot be taken out of the slotted loop because of the ring at one end and the loop 8 at the other.

80 The holes through which the eyelets are secured are also relatively large. By "relatively large", as applied to the holes and the eyelets, I intend to convey the meaning that they serve something more than a mere pivot 85 or fastening for securing the loop members to the shackle members; in particular, the eyelets are so large that when the loops are drawn forward along the leg of the animal to which the shackle is applied, the inner 90 portion of the eyelets will project inwardly into the depression immediately in front of the ham string. But in putting the shackles on or taking them off, the loops may be turned outwardly so as to permit the shackles 95 freely passing over the ham strings, as indicated in the dotted outline in Fig 1; and this free movement is permitted by reason of the relatively large holes.

100 To apply the device to the cow, the shackles are merely slipped onto the ham strings from the rear with the loops and eyelets on the outer sides of the legs and the chain in front. The chain is drawn through the slotted loop until the proper length 105 exists between the legs of the cow, and the link of the chain adjacent is slipped into the slot. The chain also draws forward the two loops so that the eyelets are projected inwardly, as explained. Should they be applied rather loosely, it will be understood 110 that any movement of the animal spreading

the legs apart would only be accompanied by a further inward projecting of the eyelets. The eyelets act as a spur,—something in addition to the sheer strength of the hopple,—
5 to dig into the animal in case it attempts to kick; and yet it causes the animal no discomfort while standing quietly.

To take the device off, the chain is pulled backward at the loop 11 to free the links 10 from the slot, and the chain is permitted to be drawn through that loop, and the shackles slipped off with the loops turned outwardly, as explained. To facilitate the taking off, however, especially when the chain is drawn 15 up tight, the extension 13 is provided to afford a hand hold for swinging the loop around to the right (viewed in Fig. 1) until it is clear of the animal's leg, to permit the more free rearward or link-releasing movement of the chain.

Having thus described my invention, what I claim is:

1. The combination of a pair of shackle members, each being formed to embrace the 25 rear and sides of an animal's leg and each being formed with two spaced holes adjacent the front end of the outer leg of such member, a pair of loops formed with eyelets engaging in the respective holes, and a chain secured at one of its ends to one of said loops and passing through the other loop, the last-named loop being formed with 30 a terminal slot communicating with the opening therethrough for locking the chain; said holes and said eyelets being relatively large so that forward pulling of the loops cause said eyelets to move across the space between the legs and so that rearward movement and the outward swinging of the loops cause said eyelets to recede therefrom.

In testimony whereof I have hereunto affixed my signature.

ALFRED B. SMITH.

Copies of this patent may be obtained for five cents each, by addressing the "Commissioner of Patents, Washington, D. C."

nal slot communicating with the opening 35 therethrough for locking the chain and with an integrally formed extension beyond said slot for manipulating said loop; said eyelets and said holes being relatively large so that rearward movement of the loops and 40 their outward swinging movement cause said eyelets to recede from the opposite leg of the shackle and so that the forward movement of the loops cause said eyelets to move inwardly across the space between the 45 shackle legs.

2. The combination of a pair of shackle members, each being formed to embrace the rear and sides of an animal's leg and each being formed with two spaced holes adjacent 50 the front end of the outer leg of such member, a pair of loops formed with eyelets engaging in the respective holes, and a chain secured at one of its ends to one of said loops and passing through the other 55 loop, the last-named loop being formed with a terminal slot communicating with the opening therethrough for locking the chain; said holes and said eyelets being relatively large so that forward pulling of the loops 60 cause said eyelets to move across the space between the legs and so that rearward movement and the outward swinging of the loops cause said eyelets to recede therefrom.
